(57) CLAIM

The ornamental design for a package for a computer input device, as shown and described.

DESCRIPTION

FIG. 1 is an isometric view of a package for a computer input device, showing my new design.

FIG. 2 is a front elevation view of a package for a computer input device, showing my new design.

FIG. 3 is a rear elevation view of a package for a computer input device, showing my new design.

FIG. 4 is a right elevation view of a package for a computer input device, showing my new design.

FIG. 5 is a left elevation view of a package for a computer input device, showing my new design.

FIG. 6 is a top plan view of a package for a computer input device, showing my new design; and,

FIG. 7 is a bottom plan view of a package for a computer input device, showing my new design.
